ATTORNEYS

UNITED STATES PATENT OFFICE.

OTTO BARTEL, OF NEW YORK, N. Y.

PENDULUM CLOCK.

SPECIFICATION forming part of Letters Patent No. 527,233, dated October 9, 1894.

Application filed June 11, 1894. Serial No. 514,153. (No model.)

To all whom it may concern:

Be it known that I, OTTO BARTEL, a resident of the city, county, and State of New York, have invented certain new and useful 5 Improvements in Mantel Pendulum Clocks, of which the following is a specification.

My invention relates to mantel pendulum clocks, and has for its object to produce a mantel pendulum clock having a pendulum 10 so constructed that the clock can be transported, shipped or tumbled about without deranging or injuring the clock.

To this end my invention consists in a clock provided with guide or guard rails and 15 with a pendulum adapted to co-operate with the rails to guide or to support the pendulum when the clock is turned into a position other than the normal position of operation. For this purpose I use preferably a rigid pendulum rod with a flexible spring at its upper 20 end hung through the slot of a stud. From this rod the ball is hung so that it can be moved up or down for regulating purposes. In clocks of this character as hitherto constructed it has been customary to suspend 25 the pendulum from one point by a flexible spring. When now the clock, by any accident, became inverted the pendulum ball became displaced and the weight thereof 30 served to bend or distort the flexible spring in such a manner as to cause the pendulum ball to swing untrue when the clock was replaced in its normal position, resulting in deranging the clock to such an extent that it 35 would stop. Now by my invention I am enabled to obviate these defects by providing an additional means for the support of the pendulum ball, which means of support is normally out of operation when the clock is 40 in its normal position of operation, but which comes into operation as soon as the clock is tilted out of the said normal position, all of which will more fully hereinafter appear.

I attain the object of my said invention by 45 means of the mechanism shown in the accompanying drawings, in which—

Figure 1 is a rear view of the retaining frame of an ordinary clock movement showing my invention applied thereto. Figs. 2, 3, 50 4, 5 and 6 show modifications of my invention. Fig. 7 is a detail view showing the preferred method of suspending the pendu-

lum rod of my said invention. Fig. 8 is a detail view of another modification of my invention. 55

In the drawings, A is one of the plates of a clock movement.

a is a slotted stud for suspending the pendulum rod, which pendulum rod may be of any ordinary construction, but which I have shown as a rigid rod b terminating in a flexible spring c passing freely through a slot in the stud a and suspended therein in any usual manner as by a stud d. Hung from the pendulum rod in any suitable manner is 65 a pendulum ball e which may be provided with means for regulating the position of the ball on the rod such as shown in Figs. 2, 3 and 4. One or more guard rails or rods f are mounted in proximity to the pendulum and 70 approximately in the plane of its swing. These rods may be mounted upon the clock case or upon the plate A in any suitable manner such as by being attached to studs g projecting from the plate A. To co-operate with 75 these guard rails or rods I provide upon the pendulum one or more guiding or suspending devices which may be of various forms and carried upon various parts of the pendulum. I have shown some of these forms 80 in the drawings, but I wish it to be understood that I do not limit myself to these forms, as other and analogous forms will readily suggest themselves to those who may desire to enjoy the fruits of my invention. 85

I have shown the guiding devices in Fig. 1 as rings h carried above and below the ball and surrounding the guard rails or rods f.

In Fig. 2, I have shown the rails or rods f as approximately parallel to the plane of the 90 swing of the pendulum and for the guiding devices I have provided staples j carried upon the pendulum ball, and it will be quite obvious (as in the preceding figure) that one of the rods and its co-operating guiding device may be omitted from this construction, 95 if desired.

In Fig. 3 I have shown the pendulum ball as grooved or recessed as at n to accommodate the guard rails f on either side of it, 100 the grooves or recesses co-operating with the guard rails to guide and support the pendulum when the clock is out of its normal position.

In Fig. 4, I have shown the guard rails as deformed from a slotted plate *k*, and for a guiding device I have shown a stud *o* projecting from the pendulum and working in the slot 5 between the rails. It will be quite obvious that this stud may be mounted upon the pendulum ball or upon the pendulum rod, as may be desired.

In Fig. 5, I have shown the pendulum ball 10 perforated, as at *l*, and the guard rail *f* as extending through the perforation.

In Fig. 6, I have shown a pair of guard rails, one on either side of the pendulum ball, and pins or studs *m* projecting from the 15 pendulum ball to co-operate with the guard rails.

In Fig. 8 I have shown a pendulum swinging between rails which are placed so near together that they will form a support for the 20 pendulum ball when the clock is inverted.

When a clock constructed in accordance with my invention is in the normal position, that is to say, when it is placed upon a level or substantially level support or mantel, the 25 swing of the pendulum will be unimpeded and the action will be the same as in any ordinary clock, and the guard rails will perform no function. If, however, the clock be inverted or held in some other unnatural position or shaken up or otherwise abused, the 30 guard rails will co-operate with the pendulum to limit the fall of the pendulum and to form additional supports for the pendulum, and will take the strain of the weight of the 35 pendulum when in these unusual positions from the flexible spring, and will prevent any flexure or other injury thereto.

If the pendulum be suspended in the preferred way, as shown in Fig. 7, and the clock 40 inverted, the pendulum ball will be supported by the guard rail or rails alone and no strain will come upon the flexible spring as the same will slide in the slot in the stud *a* and keep the position shown in dotted lines in said 45 figure.

It will thus be seen that I have produced a clock in which the pendulum will be supported independently of the usual support when the clock is placed in an unusual position 50 and in which the free swing of the pendulum will be in no wise impeded when the clock is in its normal position for operation.

While I have shown and described specific devices for accomplishing this purpose, I 55 would have it understood that I do not limit myself to the precise construction herein shown, but wish to include all equivalent

structures for attaining the end, as the devices, their construction and arrangement may be greatly varied without departing from 6c the spirit of my invention.

What I claim, and desire to secure by Letters Patent, is—

1. The combination with a pendulum, of one or more guide or guard rails mounted in proximity thereto, the said guard rails co-operating with the pendulum to guide and support the same when the pendulum has been turned to a position other than the normal operating position thereof, substantially as described. 65

2. The combination with a pendulum, of one or more guide or guard rails mounted in proximity thereto, and guiding devices upon the pendulum co-operating with the guard rails to guide and support the pendulum when the same has been turned to a position other than the 75 normal operating position thereof, substantially as described.

3. The combination of a pendulum provided with one or more guiding openings, of one or more guard rails co-operating with the guiding openings to guide and support the pendulum when the same has been turned into a position other than the normal operating position, substantially as described. 80

4. The combination of a pendulum provided with apertures, of guards or rails co-operating with the walls of said apertures, as and for the purpose as described. 85

5. An apertured pendulum in combination 90 with one or more guards or rails extending through the aperture, as and for the purpose as described.

6. The combination of a freely swinging pendulum, of supports extraneous to the pendulum, and one or more guiding devices on the pendulum normally out of engagement with the support when the pendulum is in the normal position of operation, and adapted to co-operate with the support to 100 support the pendulum when the same has been moved into a position other than the normal position of operation, substantially as described and for the purposes set forth. 95

7. In a clock movement, the combination of 105 one or more guide rails *f*, a pendulum provided with one or more rings *h* through which the guide rail or rails extend, substantially as described.

OTTO BARTEL.
